US0D1042456S

(12) **United States Design Patent** (10) **Patent No.:** **US D1,042,456 S**
(45) **Date of Patent:** **** Sep. 17, 2024**

(54) **INTELLIGENT ACCESS CONTROL DEVICE**

(71) Applicant: **Bird Home Automation GmbH**, Berlin (DE)
(72) Inventor: **Sascha Keller**, Berlin (DE)
(73) Assignee: **Bird Home Automation GmbH**, Berlin (DE)

(**) Term: **15 Years**

(21) Appl. No.: **29/844,327**

(22) Filed: **Jun. 28, 2022**

(30) **Foreign Application Priority Data**

May 4, 2022 (EM) 009015647-0001

(51) **LOC (14) Cl.** **13-03**

(52) **U.S. Cl.**
USPC **D13/162**

(58) **Field of Classification Search**

(57) **CLAIM**

The ornamental design for intelligent access control device, as shown and described.

DESCRIPTION

FIG. 1 is a front, right, top perspective view of an intelligent access control device showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

Broken lines seen in the drawings depict portions of the intelligent access control device that form no part of the claimed design.

1 Claim, 5 Drawing Sheets
